UNITED STATES PATENT OFFICE.

FREDERICK W. BALSTER, OF WILMINGTON, DELAWARE.

STEAM-BOILER.

1,327,188.

Specification of Letters Patent. Patented Jan. 6, 1920.

Application filed August 30, 1917. Serial No. 189,021.

To all whom it may concern:

Be it known that I, FREDERICK W. BALSTER, a citizen of the United States, and a resident of Wilmington, New Castle county, 5 Delaware, have invented certain Improvements in Steam-Boilers, of which the following is a specification.

My invention relates to steam boilers, and it consists of an improved form of tubular 10 boiler and an improved form of boiler shell whereby I am enabled to provide a multiplicity of heating surfaces within a compact space. In my improved structure, the walls or heating surfaces of the shells are 15 connected by a multiplicity of fire tubes, running in various directions and providing a greatly increased amount of heating surface for the volume of water and steam contained within the boiler shell.

20 My improved boiler construction may involve the use of a plurality of wall sections or plates, each of the same size, shape and arrangement; two or more of which may be assembled to provide the desired heating 25 unit for the purpose desired or required.

These and other features of my invention are more fully described hereinafter, reference being had to the accompanying drawings, in which:

30 Figure 1, is a plan view, partly in section, of my improved boiler construction.

Fig. 2, is a side elevation of the same.

Fig. 3, is a sectional view on the line III—III, Fig. 1.

35 Fig. 4, is a sectional view on the line IV—IV, Fig. 1, and

Fig. 5, is a perspective view, partly broken away, of one of the sections comprising my improved boiler construction.

40 In constructing my improved boiler, the sections may be made up of two plates of the "pan" type, which may be specially shaped by a die press or other suitable means, and then joined on a median line, 45 such as indicated at α , and secured together by welding or other suitable means.

In the drawings, 1 represents one of my improved boiler sections, and as the several 50 sections are of the same construction and arrangement, description of one will suffice for all.

The sections are made up of the plates 2 and 2^a, which may be joined together on the line α by welding the joint, using the 55 oxyacetylene flame or an electrical current, or by securing the same together in any

other suitable manner. The side walls of the plates 2 and 2^a are vertically corrugated, forming projecting ribs 3 and grooved portions 4, while the top and bottom portions 60 of these plates, including the meeting joint of the same, are similarly shaped as indicated at 5 and 6, but with the difference that the projecting portions 3 of the side walls are disposed opposite the recesses or 65 grooves 6 between the projecting portions 5 of the top and bottom walls, and vice versa. At the ends of the respective sections, the side walls of the plates are turned to form the curved walls 7, while substantially centrally of the sections the enlarged, 70 non-corrugated portions shown in the drawings may be employed. Instead of forming half sections of the "pan" type, the side walls may be independently formed and 75 joined in any desirable manner to independently formed top and bottom walls.

The side walls are spaced apart and connected together by sets of diagonally disposed open-ended fire tubes 8 and 9, extending 80 in two directions, as clearly illustrated in Figs. 3 and 4, so that the heat or other products of combustion may freely pass through the tubes to effect heating of the water within the boiler shell. 85

In addition to these diagonally disposed tubes, vertically arranged tubes 10 extend between the recessed portions of the top and bottom walls, and at the end and central portions thereof, and such disposition brings 90 said vertically arranged tubes 10 alternately with respect to the diagonally disposed tubes 8 and 9. In addition, the side walls of the boiler sections may be provided with plain end portions 11 adjoining the curved walls 95 7, and with a central portion 12 with straight side walls, and said portions 11 and 12 of the side walls are also connected together by tubes 13 substantially horizontally disposed. Certain of these tubes 13, all 100 of which are in line, may carry bolts 15, which serve to secure together a series of the boiler sections, and an outer shell 16 may be provided to inclose a series of boiler sections with which nuts 17 carried by these bolts 15 105 may engage.

Water may be introduced into the respective sections by means of a manifold 18 disposed adjacent the bottom of the shells or sections having an outlet or outlets 19 110 leading thereto, while the steam may be taken off from the top of the boiler sections

through the pipes 20 and, if desired, a super-heating manifold 21 may be placed above the sections with which said pipes communicate. The water supply is preferably disposed in the flue taking off the products of combustion in order that it may be heated before introduction to the several boiler sections.

I claim:

- 10 1. In a steam boiler, sections made up of corrugated side walls and corrugated top and bottom walls; the corrugations in the side walls being offset with respect to the corrugations in the top and bottom walls and disposed in planes parallel thereto.
- 15 2. In a steam boiler, sections made up of corrugated side walls and corrugated top and bottom walls; said side walls having rounded ends and enlarged central portions, 20 and the corrugations in the side walls being offset with respect to the corrugations in the top and bottom walls and disposed in planes parallel thereto.
- 25 3. In a steam boiler, a section made up of a pair of similar halves joined on a median line and made up of corrugated side walls and corrugated top and bottom walls; the corrugations in the side walls being offset with respect to the corrugations in the 30 top and bottom walls and disposed in planes parallel thereto.
- 35 4. In a steam boiler, a section made up of a pair of similar halves joined on a median line and made up of corrugated side walls and corrugated top and bottom walls; said side walls having rounded ends and enlarged central portions, and the corrugations in the side walls being offset with respect to the corrugations in the top and bottom walls and disposed in planes parallel 40 thereto.
- 45 5. In a steam boiler, sections comprising side walls, and top and bottom walls; the side walls being corrugated and the top and bottom walls being corrugated, and the ribs of the side wall corrugations being disposed opposite the grooves of the corrugations of the top and bottom walls; all of said corrugations lying in parallel planes.
- 50 6. In a steam boiler, a section made up of a pair of plates dished to form side walls and top and bottom walls; said plates being joined together on a median line; the side walls being corrugated and the top and bottom walls being corrugated; the ribs of the side wall corrugations being disposed in line with the grooves of the corrugations of the top and bottom walls.
- 60 7. In a sectional steam boiler, a hollow section comprising a plurality of side walls and top and bottom walls suitably joined together; the side walls being corrugated and the top and bottom walls being corrugated; the ribs of the side wall corrugations being disposed opposite the grooves of the corrugations.

gations of the top and bottom walls, and the ends of said sections being rounded.

8. In a sectional steam boiler, a hollow section made up of a pair of plates dished to form side walls and top and bottom walls; said plates being joined together on a median line; the side walls being corrugated and the top and bottom walls being corrugated; the ribs of the side wall corrugations being disposed opposite the grooves of the corrugations of the top and bottom walls, and the ends of said sections being rounded to meet on the median line.

9. The combination, in a steam boiler, of a section made up of corrugated side walls with rounded ends and corrugated top and bottom walls; said walls being suitably connected together, and fire tubes connected to and extending diagonally between the side walls.

10. The combination, in a steam boiler, of a section made up of corrugated side walls with rounded ends and corrugated top and bottom walls; said walls being suitably connected together, fire tubes connected to and extending diagonally between the side walls, and fire tubes connected to and extending vertically between the top and bottom walls.

11. The combination, in a steam boiler, of a section made up of corrugated side walls with rounded ends and corrugated top and bottom walls; said walls being suitably connected together, and fire tubes connected to and extending diagonally between the side walls and joined to the latter in the recessed portions of the same.

12. The combination, in a steam boiler, of a section made up of corrugated side walls and corrugated top and bottom walls, fire tubes extending diagonally between the side walls and joined to the latter in the recessed portions of the same, and fire tubes extending vertically between the top and bottom walls and joined to the latter in the recessed portions of the same.

13. The combination, in a steam boiler, of a section made up of side walls with rounded ends and top and bottom walls, fire tubes connected to and extending diagonally between the side walls, and fire tubes connected to and extending vertically between the top and bottom walls; the vertical fire tubes being disposed between the diagonally arranged fire tubes.

14. The combination, in a steam boiler, of a section made up of corrugated side walls and corrugated top and bottom walls, fire tubes extending diagonally between the side walls and joined to the latter in the recessed portion of the same, and vertical tubes connecting the top and bottom walls and joined to the recessed portion of the same; the vertical tubes being disposed between the diagonally arranged tubes.

15. A steam generator comprising a plu.. 110

rality of corrugated sections each having a plurality of diagonally disposed fire tubes with their ends substantially intercommunicating with the ends of adjacent tube sections, and means for securing said sections together.

16. A steam generator comprising a plurality of corrugated sections each having diagonally disposed tubes in the respective sections and vertically disposed tubes, and means for securing said sections together.

17. A steam generator comprising a plurality of corrugated sections each having diagonally disposed tubes, vertically disposed tubes and horizontally disposed tubes in registry, and bolts disposed in certain of said horizontally disposed tubes for securing the sections together.

18. A steam generator comprising a plurality of corrugated sections; the corrugations of which lie in parallel planes, and vertically disposed tubes between the top and bottom walls of said sections and connecting the recessed portions of the corrugations in said walls.

19. In a steam generator of the sectional type, a hollow unit section having a plurality of walls corrugated throughout their extent and comprising side walls with curved end portions and top and bottom walls; said section being composed of a pair of dished plates connected together on a median line with the corrugations disposed in parallel planes extending throughout the extent of said section, and a plurality of transverse tubes at right angles to the plane of its side walls carried by said section; the transverse tubes of said section being arranged to register with the transverse tubes of another section and adapted to receive bolts whereby a plurality of sections may be secured together.

20. In a steam generator of the sectional type, a hollow unit section having a plurality of walls corrugated throughout their extent and comprising side walls with curved

end portions and top and bottom walls; said section being composed of a pair of dished plates connected together on a median line with the corrugations disposed in parallel planes extending throughout the extent of said section; the external ribs of the corrugations of the side walls being opposite the recesses between the external ribs of the top and bottom walls, a plurality of fire tubes disposed between the walls of the section and connected to said walls, and a plurality of transverse tubes at right angles to the plane of its side walls carried by said section; the transverse tubes of said section being arranged to register with the transverse tubes of another section and adapted to receive bolts whereby a plurality of sections may be secured together.

21. In a steam generator of the sectional type, a hollow unit section having a plurality of walls corrugated throughout their extent and comprising side walls with curved end portions and top and bottom walls; said section being composed of a pair of dished plates connected together on a median line with the corrugations disposed in parallel planes extending throughout the extent of said section; the external ribs of the corrugations of the side walls being opposite the recesses between the external ribs of the top and bottom walls, fire tubes disposed transversely of the section and connecting the side walls thereof and lying diagonally with respect thereto, vertical fire tubes connecting the top and bottom walls; the major portion of which vertical tubes connect the recessed portions of said top and bottom walls between the external ribs thereof, transverse tubes at right angles to the plane of its side walls carried by said section; the transverse tubes of said section being arranged to register with the transverse tubes of another section, and bolts passing through said transverse tubes for securing the respective sections together.

FREDERICK W. BALSTER.
